By

Attorney.

UNITED STATES PATENT OFFICE.

JOSEPH WILLIAM HELTZEL, OF WARREN, OHIO.

CONCRETE FORM.

Application filed January 15, 1926. Serial No. 81,397.

The present invention relates to concrete forms, and more especially to forms used for the construction of concrete roads, sidewalks, platforms, and the like, employing rails or 5 form members disposed end to end.

One object of the invention is the provision of simple and effective means for holding the form members or rails in alinement.

Another object is the provision of members secured to the end portions of the rails or form members for the purpose of holding the rails or form members in alinement, and also bracing and reenforcing the end portions of the rails.

15 A further object is the provision of novel means for bracing the rails or form members to prevent lateral displacement thereof.

A still further object is to combine the bracing means with the rail joint means, and 20 a further object, in this connection, is to connect the rail joint means with stakes driven into the ground or sub-base to provide a simple and substantial form construction.

It is also an object of the invention to provide a concrete form of the kind indicated 25 providing for simplicity as well as efficiency in the joining together of the rails or form members and the bracing thereof.

With the foregoing and other objects in 30 view, which will be apparent as the description proceeds, the invention resides in the construction and arrangement of parts, as hereinafter described and claimed, it being understood that changes can be made within 35 the scope of what is claimed, without departing from the spirit of the invention.

The invention is illustrated in the accompanying drawing, wherein—

Figure 1 is a perspective view illustrating 40 the improvements.

Fig. 2 is an end view thereof.

Fig. 3 is a section on the line 3—3 of Fig. 2 taken through one of the rail joints.

The rails or rail sections 7 constituting the 45 form members or wall are composed of sheet metal and have the upright webs 8, base or bottom flanges 9 provided with upturned lips or secondary flanges 10, and tread or top flanges 11 provided with depending lips or 50 secondary flanges 12. The rails may be of different sizes and cross-sections. As shown, the base flanges 9 are wider than the tread

flanges 11, but the upper and lower flanges may be of the same or different widths. The rails are disposed end to end in alinement for defining the edge portion or side of a concrete road, sidewalk, curb, platform, or the like, while under construction, as well known in the art, with the flanges 9 and 11 disposed at the outer side of the webs 8.

In carrying out the invention a vertical bar or member 13 is welded, riveted or otherwise secured to the web 8 of each rail at each end of the rail and has its upper and lower ends bent into eyes or loops 14 and 15 providing longitudinal dowel sockets bearing against the flanges 11 and 9, respectively. Said bars or members 13 stiffen and reinforce the end portions of the rails within which they are disposed, to strengthen the 70 webs 8 and also brace the flanges 9 and 11. The bars 13 provide double thickness at the ends of the rails where the greatest strength is most needed, especially under the weight and strains of grading and finishing machines that travel on the rails. The flanges 11 are also supported at their ends by the sockets or eyes 14 to prevent said flanges being bent downwardly by the wheels of grading or finishing machines passing over the 80 rails.

When the rails are positioned end to end the upper and lower sockets 14 and 15 will register, and a dowel or pin 16 is inserted longitudinally of the rails in each pair of registering sockets 15, while a dowel or pin 22 is inserted similarly in each pair of registering sockets 14, thereby maintaining the rails in accurate alinement.

The bracing means are connected to the 90 dowels 16 and 22. Thus, a brace or bar 17 is welded or otherwise secured to each lower dowel 16 at one end thereof and extends outwardly above the corresponding flange 9 and over the flange or lip 10, and a stake socket plate 18 is welded or otherwise secured on the outer or free terminal of the brace 17 in overlapping relation therewith, and has a slot or opening 19 forming a socket for the passage of the stake 20 that is driven into the 100 ground or sub-base. The stake 20, as shown, is formed from a bar and has a lower pointed end, and a stop 21 is carried by the stake near its upper end to contact with the plate 18 and

limit the downward movement of the stake. As shown, the stake 20 is disposed immediately outside of the flange or lip 10, and the brace 17 or plate 18 thereof bears on the edge 5 of the flange 10. The brace 17 connecting the dowel 16 and stake 20 will prevent transverse displacement of the rails on the ground or sub-base. Furthermore, by driving the stake 20 down so that the stop 21 bears on the 10 plate 18, this will assist in preventing the rails from tipping inwardly, inasmuch as the brace 17 will hold the outer edge portion of the flanges 9 down on the ground or sub-base.

A brace 23 is also connected to each of the 15 upper dowels 22, and comprises the overlapping adjustably connected sections 24 and 25, the section 24 being welded or otherwise secured to the dowel 22. Bolts 26 or other clamping elements clamp the overlapping 20 portions of the sections 24 and 25 together, and said sections have slots 27 for said bolts to permit the brace 23 to be lengthened or shortened when the bolts are loosened. A 25 stake socket plate 28 is welded or otherwise secured on the outer or free terminal of the brace 23, in overlapping relation therewith, and has a slot or opening 29 providing a socket through which the stake 30 may be driven into the ground or sub-base. The 30 stake 30 has a stop 31 at its upper end to contact with the plate 28, and the stake 30 is similar to the stake 20, and said stakes may be used interchangeably. The brace 23 is inclined with its lower end outermost and connected to the stake, and with its inner end disposed immediately under the corresponding flange 11.

The braces 23 will brace the upper portions 40 of the rails to prevent them from tilting either inwardly or outwardly, and it will be noted that the braces 17 and 23 connect the stakes with the lower and upper portions of the rails in order to securely brace the rails against 45 lateral displacement either at the top or the bottom. The rails have a tendency to be displaced laterally, more especially to tip inwardly, when grading and finishing machines travel on the rails, and by the provision of the braces 17 and 23 this lateral displacement of 50 the rails is effectively eliminated. The lower braces 17 are connected with the rails immediately above the flanges 9, while the braces 23 are connected with the rails immediately 55 below the flanges 11, and the lower braces 17 not only prevent the rails from sliding laterally on the ground or sub-base but also prevent the flanges 9 from swinging upwardly due to the tendency for the rails to tilt inwardly. The stakes 20 and 30 can be relatively short inasmuch as they only extend a short 60 distance above the ground or sub-base when driven into place, so that the stakes may be somewhat shorter than stakes extending the full height (more or less) of the rails.

65 In setting up the form, the rails or form

members 7 are positioned along the ground or sub-base, in endwise abutment, in the approximate position which they are to assume when finally set. The dowels 16 and 22 are then inserted in the sockets 15 and 14, respectively, and the braces 17 and 23 swing down to bear on the flanges 10 and the ground, respectively. As shown, the dowels 16 and 22 are inserted in opposite longitudinal directions in the sockets so that the braces 17 and 23 are offset longitudinally, to prevent them from interfering. After a reasonable length of form has thus been arranged, the rails or form members are lined accurately, and the stakes are then driven through the plates 18 and 28 into the ground or sub-base. By loosening the bolts or clamping elements 26 the braces 23 may be adjusted to adjust the upper portions of the rails inwardly or outwardly into the desired line, after which the bolts 26 are tightened to maintain the adjustment of the flanges 11. If desired, the stakes 20 are not driven into place until after the stakes 30 have been driven into place and the braces 23 adjusted, inasmuch as the base or bottom flanges 9 of the rails need little or no adjustment after the flanges 11 have been adjusted, said flanges 9 assuming proper position when the flanges 11 have been adjusted to the desired line.

The construction is economical and simple, and is rigid. The dowels 16 and 22 being located at the base and tread flanges will keep the rails in accurate alignment at the bottom and top, said dowels being spaced apart vertically as far as possible. The shortest possible stakes may be used, so that they may be readily driven into place and withdrawn without being bent so readily as longer stakes, and the shorter stakes are also cheaper than longer ones. The braces and stakes prevent the rails from being displaced either outwardly or inwardly, and the bracing and staking members are combined with the dowels or joint devices so as to simplify the 100 arrangement and increase the efficiency thereof.

Should it be desired to remove one of the rails 7, the dowels 16 and 22 at the ends thereof are withdrawn from the sockets, after the corresponding stakes have been withdrawn from the ground, and this will permit the rail to be lifted or moved laterally outward, so that a truck may pass through the opening thus provided in the form. The rail may then be readily replaced. The dowels 16 and 22 and dowel sockets are of cylindrical form or circular in cross-section thus permitting the dowels to be readily inserted in the sockets and to turn therein, and the dowels provide pivot connections between the braces and rails, so that the dowels may be inserted in the sockets with the braces raised, after which the braces may swing down into place. This also enables the outer ends of 130

the braces to be positioned at different heights according to the contour of the ground or sub-base at the outer sides of the rails. The ends of the dowels are also preferably tapered 5 or pointed so as to be readily inserted in the sockets.

Having thus described the invention, what is claimed as new is:—

1. A concrete form comprising form members disposed end to end in alinement having registering sockets of circular cross section, a dowel of circular cross section inserted in said sockets and adapted to turn therein, and holding means connected to said dowel to turn therewith. 10
2. A concrete form comprising form members having vertically spaced registering sockets, dowels inserted in said sockets, and bracing means connected to the dowels. 15
3. A concrete form comprising sheet metal form members constituting a web and upper and lower flanges, a member secured to each form member and having sockets at its upper and lower ends within the bends between the 20 web and flanges of the form member to brace said flanges, said sockets of the form members registering with one another, and dowels insertable in said sockets. 25
4. A concrete form comprising sheet metal form members having webs and flanges with bends between them, members secured to the form members within said bends to brace said flanges, and adapted to register with one another, and a dowel insertable in said sockets. 30
5. A concrete form comprising form members disposed end to end in alinement, members secured to the end portions of said form members and having registering sockets, dowels inserted in said sockets, and bracing means connected to the dowels. 35
6. A concrete form comprising form members disposed end to end, vertical bars secured to the end portions of said form members and having their upper and lower ends bent to form registering sockets, and dowels inserted in said registering sockets. 40
7. A concrete form comprising form members disposed end to end and having upper and lower flanges, vertical bars secured to the end portions of said members and having their upper and lower ends formed into sockets adjacent to said flanges, and dowels inserted in said sockets. 45
8. A concrete form member having a web and flanges, and a bar secured to said web and having dowel sockets bearing against said flanges. 50
9. A concrete form member having a web and flanges, and a bar secured to said web at one end of said member and having its ends bent into dowel sockets bearing against said flanges. 55
10. In a concrete form, a form member, and a brace, said brace and form member

having portions to interengage by the movement of the brace longitudinally of the form member and permitting the form member to swing upwardly and downwardly. 65

11. In a concrete form, a form member, and a brace, said brace and form member having portions to interengage by the movement of the brace longitudinally of the form member and permitting the form member to swing upwardly and downwardly, the brace having a stake socket. 70

12. In a concrete form, a form member having a longitudinal socket, a dowel in and removable from said socket, a stake, and means secured to said dowel and having a portion to engage said stake. 75

13. In a concrete form, a form member having a longitudinal socket, a removable dowel in said socket, a stake, and a brace secured to said dowel and having a portion to engage the stake. 80

14. A form member having a longitudinal socket, a removable dowel in said socket, and a brace connected to said dowel. 85

15. A form member having a longitudinal socket, a removable dowel in said socket, and a brace connected to said dowel having a stake socket. 90

16. In a concrete form, a form member having a longitudinal socket, a removable dowel in said socket, a stake, and adjustable means secured to said dowel and having a portion to engage the stake. 95

17. In a concrete form, a form member having a longitudinal socket, a removable dowel in said socket, a stake, and an adjustable brace connecting said dowel and stake. 100

18. In a concrete form, a form member, and a longitudinally adjustable brace, said form member and one end of the brace having portions to interengage by the movement of the brace longitudinally of the form member and permitting upward and downward swinging movement of the brace, said brace having stake engaging means at its other end. 105

19. In a concrete form, a form member, and a longitudinally adjustable brace having one end pivotally connected with the form member for the upward and downward swinging movement of the brace and having a stake socket at its other end. 110

20. In a concrete form, a form member having a web and an outstanding flange, and a brace pivotally connected with said form member adjacent to the web thereof to swing against said flange. 115

21. In a concrete form, a form member having a web and an outstanding flange, and a brace pivotally connected with said form member adjacent to the web thereof to swing against said flange and having a stake socket beyond said flange. 120

22. In a concrete form, a form member having a longitudinal socket and a flange, a

- removable dowel in said socket, and a brace connected to said dowel and adapted to bear against said flange.
23. In a concrete form, a form member having a longitudinal socket and a flange, a removable dowel in said socket, and a brace connected to said dowel and adapted to bear against said flange and having a stake socket beyond said flange.
- 16 24. In a concrete form, a form member having a web and a base flange, and a brace pivotally connected with said member adjacent to the web thereof to swing down against said flange.
- 15 25. In a concrete form, a form member having a web and a base flange, and a brace pivotally connected with said member adjacent to the web thereof to swing down against said flange and having a stake socket beyond said flange.
- 20 26. In a concrete form, a form member, and braces pivotally connected with said form member at vertically spaced points to swing upwardly and downwardly.
- 25 27. In a concrete form, a form member, and braces pivotally connected with said form member at vertically spaced points to swing upwardly and downwardly and having stake sockets.
- 30 28. In a concrete form, a form member having vertically spaced sockets, removable dowels in said sockets, and braces connected to said dowels to swing upwardly and downwardly.
- 35 29. In a concrete form, a form member having upper and lower flanges, and braces pivotally connected with said form member immediately below and above the upper and lower flanges, respectively.
- 40 30. In a concrete form, a form member having upper and lower flanges, sockets carried by said member immediately below and above said upper and lower flanges, respectively, removable dowels in said sockets, and braces connected to said dowels.
- 45 31. A concrete form comprising form members disposed end to end and having upper and lower flanges, and braces pivotally connected with said form members adjacent to said upper and lower flanges.
- 50 32. A concrete form comprising form members disposed end to end and having upper and lower flanges, braces pivotally connected with said form members and adapted to bear on the lower flanges and having stake engaging means, and adjustable braces pivotally connected with said members adjacent to the upper flanges.
- 55 33. A concrete form comprising form members disposed end to end and having upper and lower flanges, upper and lower sockets carried by said members adjacent to said upper and lower flanges, respectively, removable upper and lower dowels in said sockets, braces connected to the lower dowels and 65 adapted to bear on the lower flanges, and longitudinally adjustable braces connected to the upper dowels.
34. In a concrete form, a form member, and braces pivotally connected with the form member at vertically spaced points and having means to engage different stakes.
35. In a concrete form, a form member, and braces pivotally connected at vertically spaced points with said member to swing upwardly 75 and downwardly and having stake sockets to receive different stakes.
36. A brace for a concrete form having a transversely projecting dowel secured to one end thereof and stake engaging means at its 80 other end.
37. A brace for a concrete form having a transversely projecting dowel secured to one end thereof to engage in a socket for the swinging movement of the brace, and having a stake socket at its other end.
38. A brace for a concrete form comprising adjustably connected sections, one section having a transversely projecting dowel secured thereto and the other section having 90 stake engaging means.
39. A concrete form comprising form members disposed end to end in alinement, a dowel engaging them to hold them in alinement, a stake, and means secured to said dowel and having a portion to engage said stake.
40. A concrete form comprising form members disposed end to end in alinement, a dowel engaging them to hold them in alinement, a 100 stake, and a brace secured to said dowel and having a portion to engage said stake.
41. A concrete form comprising form members disposed end to end in alinement, registering sockets carried thereby, a removable 105 dowel in said sockets for holding the form members in alinement, a stake, and means secured to said dowel and having a portion to engage said stake.
42. A concrete form comprising form members disposed end to end in alinement, registering sockets carried thereby, a removable dowel in said sockets for holding the form members in alinement, a stake, and a brace 110 secured to said dowel and having a portion to engage said stake.
43. A concrete form comprising form members, registering sockets carried thereby, a removable dowel in said sockets to hold the form members in alinement, and a brace connected to said dowel 115 to engage said stake.
44. A concrete form comprising form members, registering sockets carried thereby, a removable dowel in said sockets to hold the form members in alinement, and a brace connected to said dowel to swing upwardly and downwardly and having a stake socket.
45. A concrete form comprising form mem-

bers disposed end to end and having upper and lower flanges, registering sockets carried by said members adjacent to said flanges, removable dowels in said sockets, and braces connected to said dowels.

46. A concrete form comprising form members disposed end to end and having upper and lower flanges, upper and lower registering sockets carried by said members immediately below and above the upper and lower flanges, respectively, removable dowels in the registering sockets, and braces secured to said dowels and having stake sockets beyond said flanges.

47. A concrete form comprising form members disposed end to end and having upper and lower flanges, registering sockets carried by said members immediately below and above said upper and lower flanges, respectively, upper and lower dowels removably disposed in the upper and lower sockets, respectively, braces connected to the lower dowels and adapted to bear downwardly on the

lower flanges, and adjustable braces connected to the upper dowels.

48. A concrete form comprising form members disposed end to end, and means joining said members together and having upwardly and downwardly movable braces connected thereto at vertically spaced points and provided with stake engaging means.

49. A concrete form comprising form members disposed end to end, joint means connecting said members to hold them in alignment, and a brace connected to said means to swing upwardly and downwardly and having stake engaging means.

50. A concrete form comprising form members disposed end to end, joint means connecting said members to hold them in alignment, and braces connected to said means at vertically spaced points and having stake engaging means.

In testimony whereof I hereunto affix my signature.

JOSEPH WILLIAM HELTZEL.
